HOT GAS AGITATOR FOR HEATERS

Ralph Anthony Krauss, Philadelphia, Pa., assignor to Anthracite Equipment Corporation, Wilkes-Barre, Pa., a corporation of Delaware

Application June 25, 1947, Serial No. 756,987

4 Claims. (Cl. 110—97)

1

The present invention relates to heaters and more particularly to a device for increasing the efficiency of boilers and heaters.

An object of the invention is to provide means for securing greater heat absorption per unit of heating surface. An important feature of the invention in that connection is the provision of a device which impels the hot gases from the furnace fire bed along the heat absorbing walls of the furnace; thereby obtaining marked increase in the absorption of heat by said walls, and greatly increasing the furnace efficiency without the addition of large areas of heating surface.

The invention, more specifically, provides a fan or agitator which is arranged to draw hot gases from the fire bed and to force them along heat-absorbing furnace walls. The fan or agitator may be so arranged as to impel the gases repeatedly and at high velocity against the same surface areas of a heater as are exposed in the conventional heater to gases which impinge thereon only once and at relatively low velocity. It may effect repeated circulation of the hot gases in the combustion chamber at high velocity, thereby contributing still further to increase of heat output without change of dimensions of either heater or chimney.

Other features and advantages of the invention will be hereinafter described and claimed.

In the accompanying drawings Fig. 1 represents a sectional elevation of a heating apparatus embodying the present invention; Fig. 2 represents a perspective of the form of agitator shown in Fig. 1; Fig. 3 represents a sectional elevation of a heater equipped with another form of agitator; Fig. 4 represents a perspective of the agitator shown in Fig. 3; and Fig. 5 represents a detail in bottom plan of the agitator shown in Fig. 3.

Referring to the drawings one form of the present invention is shown in Fig. 1 as including a chamber 10 of a boiler or heater 11 of any well known type for heating water or air as the case may be. As shown, the heater 11 is of the coal fired type having a coaling door 12 opening to the chamber 10 above a grate 13, and also having a gas outlet 14 leading to the flue or chimney. The heater walls, as shown, may be hollow to provide a jacket adapted to contain water or other suitable fluid medium to be heated.

It will be noted that in this embodiment the lower wall portion of the chamber 10 surrounds a fire bed on the grate 13; while the upper wall portion extends beyond said fire bed. The inner surfaces of said upper wall portion thus absorb heat from the combustion gases emerging from

2

said bed and transfer said heat to the water or other fluid medium in the surrounding jacket.

For creating turbulence of the gases within the combustion chamber 10 in order to project the combustion gases violently against the heating surfaces, a rotary impeller 15 is mounted coaxially within the chamber 10 on a shaft 16 which is suitably journaled in a sleeve 17 passing through the dome 18 of the heater 11. A stuffing box 20 serves to prevent gas leakage along the shaft 16 to the exterior of the heater. The impeller 15 may be of any suitable type. As shown, it may comprise radial blades 21 extending from a suitable hub secured to the shaft 16. The projecting end of the shaft sleeve 17 is anchored by attachment to the horizontal arm 22 of a wall bracket 23, while the shaft 16 passes through an opening 24 provided in the arm 22.

For driving the shaft 16 at a selected speed the motion transmitting means, shown by way of example, includes a pulley 25 fast on the shaft 16 and driven by a belt 26 from a second pulley 27 keyed or otherwise made fast to the shaft 28 of an electric motor 30. This latter is carried by the bracket 23. The speed for best results can be obtained by variation of pulley diameters as well understood.

Preferably the impeller 15 is located well within the dome 18 and above the gas outlet 14 but the invention is not limited to this precise assembly since advantageous results may be obtained by positioning the impeller in closer proximity to the fuel bed.

In the form of the invention shown in Figs. 3 and 4 an impeller of fan wheel type is shown attached to the shaft 16 to receive rotary motion therefrom. In this type the impeller is formed by two spaced circular plates 31 and 32 having vanes 33 around the periphery and connecting the marginal rims of the two plates 31 and 32. The plate 32 is provided with an axial opening 34 so that gases are drawn inward and projected radially outward by the vane structure to produce the desired gas circulation or turbulence. Preferably this type of impeller or agitator is provided with a cylindrical baffle 35 of slightly larger diameter than the impeller and mounted coaxially below the inlet plate 32, being suspended from the sleeve 17 by angle arms 36. Thus when mounted within the combustion chamber of a heater, rotation of the impeller draws gases upwardly through the baffle 35 and discharges them radially outward to thus create such turbulence as will project the combustion gases violently against the heating surfaces.

It will now be apparent that a complete unitary device has been devised for agitating the hot gases in a heater or boiler so that those gases flow along the heat-absorbing surfaces at high velocity. The high velocity flow of the gases along the heat-absorbing surfaces greatly increases the rate of heat transfer between said gases and said surfaces. In addition, the rapid impingement of the gases against said surfaces produces a pronounced scrubbing effect which maintains the surface clean and further accentuates the rate of heat absorption. As a result, maximum heat absorption is maintained, and the heating surfaces of the boiler may be materially reduced. A substantial amount of heat units, which heretofore have been lost in the chimney or flue, now become available and useful. Also, for a given stack draft condition the rate of combustion is materially increased.

In both forms of impellers used the rotative speed is preferably such that the impeller will handle several times the amount of gas given off by the fuel bed, so that the gases are forced to circulate in a closed path several times before passing to the chimney.

While in the foregoing the surfaces against which the gases impinge at high velocity are illustrated as those in the combustion chamber, the invention, in its broader aspects, is not limited thereto since many heaters have not only these combustion-chamber heating surfaces but also supplemental heating surfaces in chambers through which the gases travel after leaving the combustion chamber. Broadly, therefore, the invention includes apparatus for impelling the hot gases at high velocity against heat absorbing surfaces whether in the combustion chamber or in chambers supplemental thereto.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. In combination, heating apparatus having a wall portion defining a chamber for a fire bed, and also having a wall portion rigid with the first-mentioned wall portion and extending beyond the same to provide a heat-absorbing chamber in communication with said fire bed chamber for receiving combustion gases from said bed and transferring heat from said gases to a fluid medium, said apparatus also having an opening for the escape of said gases from the second mentioned wall portion, a device comprising rotary blades extending substantially entirely out of alignment with said opening for causing said gases to recirculate along inner surfaces of said second mentioned wall portion, and means forming a positive drive connected with said rotary blades.

2. In combination, heating apparatus having a wall portion defining a chamber for a fire bed, and also having a wall portion rigid with the first-mentioned wall portion and extending beyond the same to provide a heat-absorbing cham-

ber in communication with said fire bed chamber for receiving combustion gases from said bed and transferring heat from said gases to a fluid medium, said apparatus also having an opening for the escape of said gases from the second mentioned wall portion, a device comprising rotary blades extending substantially entirely out of alignment with said opening for causing said gases to impinge repeatedly and at increased velocity against the inner surfaces of said second mentioned wall portion, and means forming a positive drive connected with said rotary blades.

3. In combination, heating apparatus having a wall portion defining a chamber for a fire bed, and also having a wall portion rigid with the first-mentioned wall portion and extending beyond the same to provide a heat-absorbing chamber in communication with said fire bed chamber for receiving combustion gases from said bed and transferring heat from said gases to a fluid medium, said apparatus also having an opening for the escape of said gases from the second mentioned wall portion, an impeller comprising blades extending substantially entirely out of alignment with said opening for causing a flow of gases longitudinally within the second mentioned wall portion toward said opening and along the inner surfaces of said second mentioned wall portion, and positive means for rotating said impeller.

4. In a heating apparatus the combination of a heating unit including a fire bed chamber, a heat-absorbing chamber rigid with said fire bed chamber and in communication therewith for receiving combustion gases from said fire bed chamber, and surrounding heating surfaces, a flue outlet for products of combustion, means to admit fuel into said fire bed chamber, means comprising rotary blades extending substantially entirely out of line with said outlet to cause said products of combustion to impinge more than once upon said heating surface, whereby available heat units normally escaping to said flue outlet are utilized in the heating of said surfaces, and means forming a positive drive connected with said rotary blades.
